UNITED STATES PATENT OFFICE

RALPH C. FAULKNER, OF BROOKLYN, NEW YORK, ASSIGNOR TO E. R. SQUIBB & SONS,
OF NEW YORK, N. Y., A CORPORATION OF NEW YORK

DESIGN FOR A BOTTLE

Application filed October 3, 1930. Serial No. 37,120. Term of patent 14 years.

To all whom it may concern:

Be it known that I, RALPH C. FAULKNER, a citizen of the United States, residing at 36 Clinton Street, Brooklyn, New York, have invented a new, original, and ornamental Design for a Bottle, of which the following is a specification, reference being had to the accompanying drawing, forming a part thereof.

Figure 1 is a front view;

I claim:

The ornamental design for a bottle substantially as shown.

In the drawing of the bottle:

RALPH C. FAULKNER.
